US00D872943S

(12) **United States Design Patent** (10) **Patent No.:** **US D872,943 S**
(45) **Date of Patent:** **** Jan. 14, 2020**

(54) **MANDIBLE GUARD**

- (71) Applicant: **RM Soldier Systems, Ltd.,**
Wilmington, DE (US)
- (72) Inventors: **Edward R. Hall**, Starksboro, VT (US);
Stéphane Lebel, St. Redempteur (CA);
Dominic Giroux Bernier, St-Gabriel de
Brandon (CA); **Bastien Jourde**,
Montréal (CA); **Philippe Lefebvre**,
Montréal (CA); **Hugues Rivest**,
Montréal (CA)
- (73) Assignee: **RM Soldier Systems, Ltd.,**
Wilmington, DE (US)

(**) Term: **15 Years**

(21) Appl. No.: **29/638,283**

(22) Filed: **Feb. 26, 2018**

Related U.S. Application Data

- (62) Division of application No. 29/579,739, filed on Oct. 3, 2016, now Pat. No. Des. 814,707.

(57) **CLAIM**

The ornamental design for a mandible guard, as shown and described.

DESCRIPTION

FIG. 1 is a top, front, right side perspective view of a mandible guard showing our new design;

FIG. 2 is a front view thereof;

FIG. 3 is a rear view thereof;

FIG. 4 is a left side elevation view thereof;

FIG. 5 is a right side elevation view thereof;

FIG. 6 is a top plan view thereof; and,

FIG. 7 is a bottom plan view thereof.

The broken lines illustrate portions of the mandible guard that form no part of the claimed design.
